ANIMATED JIG-SAW PUZZLES

Filed Oct. 1, 1949

UNITED STATES PATENT OFFICE

2,585,419

ANIMATED JIGSAW PUZZLE

Dominic A. Zarlengo, Denver, Colo.

Application October 1, 1949, Serial No. 119,081

4 Claims. (Cl. 273—157)

1

This invention relates to what might be termed an animated jig-saw puzzle, and has for its principal object, the provision of a jig-saw puzzle which can be assembled in the usual jig-saw style, and in which, after assembly, movement may be imparted to the various figures thereof to give an animated effect to the complete puzzle.

Another object of the invention is to provide means incorporated in the jig-saw pieces themselves for transmitting movement from one figure to another so that all elements in each completed puzzle will move in unison when any of the figures of the completed puzzle picture are moved.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a face view of a back board designed to receive the elements of the improved jig-saw puzzle;

Fig. 2 is a cross-section through the board of Fig. 1, taken on the line 2—2, Fig. 1;

Fig. 3 illustrates a group of puzzle pieces to be used for completing a picture puzzle on the board of Fig. 1;

Fig. 4 illustrates the puzzle pieces of Fig. 3 in their proper places on the board of Fig. 1; and

Fig. 5 is a fragmentary, detail view, illustrating an alternate form of mounting puzzle pieces on the board.

The invention is applicable to an endless variety of different pictures and puzzles. Only a typical one of these is illustrated in the drawing, it being understood that the pieces and the picture may be varied to suit any desired composition.

The playing board comprises a solid backboard 10, preferably having a raised border strip 11. The board is provided with fixed design portions which are secured to the backboard 10 and become a permanent part of the complete board. These fixed design portions, of course, depend in design upon the particular picture being depicted upon the board.

The picture depicted upon the drawing is "Humpty Dumpty," and to carry this out a fixed block 12 representing a portion of a wall; a sec-

2

ond block 13 representing the foreground in front of the wall; and a fixed block 14 representing a castle in the distance, are permanently mounted on the backboard 10, and form a part thereof. These blocks and the face of the board are suitably ornamented to form the background or fixed portions of the picture.

The fixed blocks and the border strip 11 are uniform in thickness. The wall block 12 is provided with a circular notch 16, and the foreground block 13 is also provided with similar circular notches 17 and 18.

The "Humpty Dumpty" picture illustrated depicts "Humpty Dumpty" himself, together with the "knight" and a "dog." The puzzle pieces for assembling this particular picture are designated by numeral for identification purposes in the various views by the numerals 19 to 26 inclusive. Certain of these pieces have simply the usual jig-saw contour to allow them to be fitted together in fixed relation. Others are designed to provide movement to the assembled figures.

Attention is called to piece 23, which is provided with a substantially circular tab 29 which 25 rotatably fits into the circular notch 16 of the wall block 12, and to pieces 22 and 26, which are provided with substantially circular tabs 30 and 31 which fit into the notches 17 and 18, respectively of the foreground block 13. These circular tabs and their respective circular notches allow the figure pieces to rotate about the axis of the circular notches.

Means are provided in various ways for transmitting the movement from one completed picture figure to another. In the embodiment illustrated, connecting link members 27 and 28 are provided. The link member 27 is formed with a rounded notch 32 at its one extremity and a similar notch 33 at its other extremity. The notch 32 receives a circular tab 34 on the piece 24, and the circular notch 33 hooks into a circular socket 35 to transmit movement from the "knight" to "Humpty Dumpty."

The link 28 is provided with substantially circular notches 36 for receiving rounded tabs 37 on the pieces 22 and 26 to transmit movement from the "knight" to the "dog" of the particular picture illustrated.

The puzzle pieces of Fig. 3 are assembled into 50 the board of Fig. 1 similarly to the usual assembly of a jig-saw puzzle, the final result appearing as in Fig. 4.

It can be seen that if movement is imparted to any of the figures of the picture, this movement will be transmitted to all of them to cause

the "knight" to rock back and forth on his horse simultaneously with the rocking movement of "Humpty Dumpty" on the wall and the dog in the foreground. Guide blocks, such as illustrated at 15, may be employed to assist in holding the connecting members in place if desired.

While the figures of Fig. 4 have been connected by connecting link members, movement could also be imparted from one figure of a picture to another by having a portion of one figure inserted into a receiving notch in another figure. Such a construction is illustrated in Fig. 5, wherein a rounded projecting portion 39 of a figure 38 is inserted into a receiving notch in a second figure 40, to transmit movement to the latter.

The completed figures in the picture of Fig. 4 all rotate about axes external of the figures. They could, however, be arranged to rotate about axes internal of the figures if desired. Such a construction is indicated by the circular bosses 41 and 42 of Fig. 5 which are fixed to the back-board and over which figures 38 and 40 are placed, the latter being provided with circular openings for receiving the bosses. It can be readily seen that the entire figures may be rotated about the axes of the bosses 41 and 42.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. An animated jig-saw puzzle comprising: a backing board, flat fixed picture portions mounted in spaced predetermined positions on the front face of said board, a plurality of picture units lying flat against said backing board in the same plane as the fixed picture portions and capable of oscillatory movement, coacting means between the movable picture units and the respective fixed picture portions to rockably connect the units to the respective fixed picture portions, and means operatively connecting the movable units to one another for causing all of said movable units to oscillate on said backing board when one of said movable units is manually oscillated.

2. An animated jig-saw puzzle comprising: a backing board, flat fixed picture portions mounted in spaced predetermined positions on the front face of said board, a plurality of independent picture units lying flat against said backing board in the same plane as the fixed picture portions and capable of oscillatory movement, each of said picture units being formed from a plurality of flat interfitting picture puzzle pieces, coacting means between the movable picture units and the respective fixed picture portions to rockably connect the units to the respective fixed picture portions, and means operatively connecting the movable units to one

another for causing all of said movable units to oscillate on said backing board when one of said movable units is manually oscillated.

3. An animated jig-saw puzzle comprising: a backing board, flat fixed picture portions mounted in spaced predetermined positions on the front face of said board, a plurality of independent picture units lying flat against said backing board in the same plane as the fixed picture portions and capable of oscillatory movement, each of said picture units being formed from a plurality of flat interfitting picture puzzle pieces, coacting means between the movable picture units and the respective fixed picture portions to rockably connect the units to the respective fixed picture portions, and means operatively connecting the movable units to one another for causing all of said movable units to oscillate on said backing board when one of said movable units is manually oscillated, said last mentioned means comprising link members extending between and operatively connected to the movable units.

4. An animated jig-saw puzzle comprising: a backing board, flat fixed picture portions mounted in spaced predetermined positions on the front face of said board, a plurality of independent picture units lying flat against said backing board in the same plane as the fixed picture portions and capable of oscillatory movement, each of said picture units being formed from a plurality of flat interfitting picture puzzle pieces, coacting means between the movable picture units and the respective fixed picture portions to rockably connect the units to the respective fixed picture portions, said coacting means comprising a substantially circular shaped tab formed on the edge of one of the movable picture units and a substantially circular shaped notch in the adjacent edge of the complementary fixed picture portions receiving the respective tab, and means operatively connecting the movable picture units to one another for causing all of said units to oscillate on said backing board when one of said picture units is manually oscillated.
